UNITED STATES PATENT OFFICE.

ANDRÉ M. MERTZANOFF, OF BUFFALO, NEW YORK, ASSIGNOR TO AMERICAN RADIATOR COMPANY, OF CHICAGO, ILLINOIS, A CORPORATION OF NEW JERSEY.

HEATING APPARATUS.

Application filed October 18, 1917. Serial No. 197,289.

To all whom it may concern:

Be it known that I, ANDRÉ M. MERTZANOFF, a subject of the King of Greece, residing at Buffalo, Erie County, in the State of New York, have invented certain new and useful Improvements in Heating Apparatus, of which the following is a full, clear, and exact specification.

My invention relates to improvements in 10 heating apparatus, and the same has for its object, more particularly, to provide a combined boiler and radiator which is adapted to heat directly the room or chamber in which said apparatus is located, and also to 15 heat indirectly other rooms or chambers proximately or remotely situated with reference to the room or chamber in which said combined boiler and radiator is located.

Further said invention has for its object 20 to provide a combined boiler and radiator which is so constructed and proportioned that the outer surface of said apparatus will serve to heat the room or chamber within 25 which said apparatus is disposed, while the inner surface of said apparatus will serve as a heat absorber to produce the heating medium serving to heat the rooms or chambers other than the one in which said combined boiler and radiator is disposed.

Further said invention has for its object 30 to provide a combined boiler and radiator which is so constructed that its outer surface may be increased or diminished to suit the capacity of the room or chamber in which 35 the same is located, and its inner surface may be correspondingly enlarged or reduced to suit the capacity of the secondary heating apparatus located in the other rooms or chambers.

Further said invention has for its object 40 to provide a heating apparatus of the character above specified in which the outer or heat-emitting surface is substantially double its inner or heat-absorbing surface.

Further said invention has for its object 45 to provide a combined boiler and radiator which shall be neat, compact and efficient, and in general resemble an ordinary radiator.

Other objects will in part be obvious and 50 in part be pointed out hereinafter.

To the attainment of the aforesaid objects and ends my invention consists in the novel details of construction, and in the combination, connection and arrangement of parts

hereinafter more fully described and then pointed out in the claims.

In designing and manufacturing boilers for use in connection with house heating systems it is always sought to make the heat 60 absorbing surfaces, i. e., the interior surfaces of the boiler exposed to the fire, as large as possible, and the heat radiating surfaces, i. e., the exterior or exposed surfaces of the boiler, as small as possible. That is to say, 65 the object is to prevent as far as possible all heat loss due to radiation, and in order more effectually to accomplish this result boilers are frequently jacketed or enveloped with a heat lagging substance or material, as boilers 70 are usually located in cellars or boiler rooms which are not required to be heated.

In boilers, as generally manufactured, roughly speaking, the area of the interior or heat-absorbing surface is usually double that 75 of the exterior or radiating surface of the boiler.

My present invention has for its object to provide a boiler more particularly adapted for use in small buildings, such as 80 bungalows, which are not provided with cellars, and in apartments wherein the several rooms are all upon one floor or level. My invention has also, as one of its principal 85 objects, to provide a boiler in which the area of its exterior or radiating surface is, roughly speaking, double that of its interior or heat absorbing surface in order that said boiler shall act as a heat emitting apparatus serving to directly heat the room or chamber 90 in which the same is located.

In the accompanying drawings forming part of this specification wherein like numerals of reference indicate like parts,

Figure 1 is a front elevation showing one 95 form of combined boiler and radiator constructed according to, and embodying my said invention;

Fig. 2 is a side elevation;

Fig. 3 is a rear elevation;

Fig. 4 is a detail face view showing the construction of one of the intermediate sections of my combined boiler and radiator;

Fig. 5 is a transverse section taken on the line 5—5 of Fig. 1, and

Fig. 6 is a similar view taken on the line 6—6 of Fig. 1.

Referring to the drawings 10 designates the apparatus as a whole comprising front and back sections 11, 12, respectively, which 110

are provided at their lower ends with supporting legs 13, 13. 14, 14, denote intermediate sections which correspond in exterior outline with the front and back sections 11, 12.

The front section 11 comprises a water compartment having parallel front and rear walls and having convex peripheral walls in order to increase the outer or radiating surface thereof. Openings are provided in the front section to afford access to the interior of the combined boiler and radiator and these openings are normally closed by hinged doors which are supported upon plates secured to the front wall of the section. As shown there are four doors 15, 16, 17 and 18. The door 15 registers with the flue at the top of the apparatus hereinafter described, and serves to permit the cleaning thereof. The door 16 registers with the fuel charging opening in the front section 11 and communicates with the fuel chamber. The door 17 covers the slicing or poking opening and may, if desired, be provided with transparent windows 19 to permit the fire to be seen when the door is closed. The door 18 is the ash pit door and is provided with the usual sliding damper 20 to regulate the draft.

The back section 12 is similar in construction to the front section but is provided with one opening only which is positioned at the top thereof and registers with the flue. A casting 21 secured to the back section in registry with the flue opening is provided with means for attachment to the smoke pipe and with a suitable damper 22 to control the draft.

Each intermediate section is provided with a water compartment comprising vertical hollow members 23, with convex peripheral surfaces extending throughout the height of the section, communicating with one another by transverse hollow members 24, 25 and 26; the transverse members 24 and 26 being positioned at the top and bottom of the section respectively and the transverse member 25 being disposed below the upper transverse member 24 a distance sufficient to form a main flue 27 when the sections are assembled. The upper portions of the vertical hollow members 23 extend inwardly beyond the lower portions thereof and are provided with laterally extending fins 28, which, when the sections are assembled, abut the fins of adjacent sections to form vertical flues 29 communicating at their lower ends with the combustion chamber 30 and at their upper ends with the flue 27.

Communication between the water compartments of the several sections is established by means of openings 31 and 32 at the top and bottom thereof which receive nipples 33.

A shaking grate 34 is provided intermediate the combustion chamber and ash pit, and is adapted to be actuated by a suitable crank 35 in the usual manner.

Below the grate 34 the intermediate sections are provided with downwardly and inwardly inclined fins 36 in order to direct the ashes away from the sides of the ash pit.

To heat a room other than the one in which the apparatus 10 is located, the heated fluid is led from the apparatus by a pipe 37 to a radiator in such other room from which it is returned to the apparatus by a pipe 38 communicating with the back section 12 at the bottom thereof.

By reason of the fact that the water compartments extend throughout the sides, top and bottom of the apparatus and are provided with convex peripheral or radiating surfaces, and by reason of the fact that the supporting legs 13 insure that the bottom portions of the water compartments will be spaced from the floor of the room in which the apparatus is positioned, an outer or heat radiating surface is provided which is materially greater than the inner or heat absorbing surface. In actual practice the parts are preferably so proportioned that the total area of the outer or heat emitting surfaces of the apparatus shall be substantially double that of the area of the interior or heat absorbing surfaces.

In the specification and in the claims the applicant, in referring to the ratio which the external or heat emitting surface bears to the interior or heat absorbing surface, has used the terms "roughly speaking double;" "substantially double," and "materially greater" to indicate the ratio which said surfaces bear to one another. Where the said terms are used the same are intended to include constructions in which, for example, the ratio for an apparatus comprising four sections is not materially in excess of 2.17; for an apparatus comprising, for example, eight sections is not materially less than 1.68, and for the other sizes is correspondingly proportionate.

Having thus described my said invention, what I claim and desire to secure by Letters Patent is:—

1. An apparatus of the character described comprising end and intermediate sections enclosing a fire pot and a combustion chamber; each of said intermediate sections including a continuous, peripheral water compartment having inwardly projecting portions extending downwardly from the upper end of said combustion chamber and terminating intermediate the upper and lower ends thereof, said portions forming passages to conduct the products of combustion from said combustion chamber; the outer exposed

- wall portions of said sections constituting the heat emitting surfaces whose total area is substantially double that of the interior wall portions which constitute the heat absorbing surfaces, substantially as specified.
2. An apparatus of the character described comprising end and intermediate sections enclosing a fire pot, a combustion chamber, and a main flue positioned above 10 said combustion chamber; each of said intermediate sections including a continuous, peripheral water compartment having inwardly projecting portions extending downwardly from the upper end of said combustion chamber and terminating intermediate the upper and lower ends thereof, said portions forming passages to conduct the products of combustion from said combustion chamber to said main flue, substantially as 20 specified.
3. An apparatus of the character described comprising end and intermediate sections enclosing a fire pot, a combustion chamber, and a main flue positioned above 25 said combustion chamber; each of said intermediate sections including a continuous, peripheral water compartment having inwardly extending portions extending downwardly from the upper end of said combustion chamber and terminating intermediate the upper and lower ends thereof, said portions forming passages to conduct the products of combustion from said combustion chamber to said main flue; the outer exposed 30 wall portions of said sections constituting the heat emitting surfaces whose total area is substantially double that of the interior wall portions which constitute the heat absorbing surfaces, substantially as specified.
4. An apparatus of the character described comprising end and intermediate sections enclosing a fuel receptacle, a combustion chamber and a main flue; each of said intermediate sections including a continuous 40 peripheral water compartment having inwardly-extending lateral water members adjacent to its upper portion forming the side walls of said combustion chamber and forming a plurality of passages therebetween to 45 conduct the products of combustion from said combustion chamber to said main flue, substantially as specified.
5. An apparatus of the character described comprising end and intermediate sections enclosing a fuel receptacle, a combustion chamber and a main flue; each of said intermediate sections including a continuous 55 peripheral water compartment having a plurality of parallel lateral water members adjacent to its upper portion forming the side walls of said combustion chamber and forming a plurality of passages therebetween to 60 conduct the products of combustion from said combustion chamber to said main flue, substantially as specified.
6. An apparatus of the character described comprising end and intermediate sections enclosing a fuel receptacle, a combustion chamber and a main flue; each of said intermediate sections including a continuous 70 peripheral water compartment having a plurality of parallel water members extending inwardly from the opposite sides of the apparatus above said fuel receptacle and forming therebetween passages to conduct the 75 products of combustion from said combustion chamber to said main flue, substantially as specified.
7. An apparatus of the character described comprising end and intermediate 80 sections enclosing a fuel receptacle and a combustion chamber; said intermediate sections having registering openings therein forming a main flue, and each of said intermediate sections including a continuous peripheral water compartment having a plurality of separated inwardly extending water members intermediate said fuel receptacle and said main flue; the spaces intermediate 85 said inwardly extending water members forming passages for conducting the products of combustion from said combustion chamber to said main flue, substantially as specified.
8. An apparatus of the character described comprising end and intermediate sections; said intermediate sections each including a continuous, peripheral water compartment and said sections enclosing an ash pit, a fire pot, a combustion chamber having a reduced upper portion, a main flue positioned above said combustion chamber, and hollow water sections extending inwardly from the sides of said peripheral water compartment serving to form the reduced upper portion of said combustion chamber and forming passages therebetween for conducting the products of combustion to said main flue; the outer exposed wall portions of said sections constituting the heat emitting surfaces whose total area is substantially double that of the interior wall portions which constitute the heat absorbing surfaces, substantially as 95 specified.
9. An apparatus of the character described comprising end and intermediate sections, said intermediate sections each including a continuous, peripheral water compartment, said sections enclosing an ash pit, a fire pot, a combustion chamber above said fire pot, having a reduced upper portion, flues extending from said fire pot inwardly between the side walls of said combustion chamber and the outer walls of said apparatus and coextensive in height with the height of the reduced upper portion of said combustion chamber, and a flue communicating with said flues and a smoke outlet; the outer exposed wall portions of said sections con- 100
- 110
- 115
- 120
- 125
- 130

stituting the heat emitting surfaces whose total area is substantially double that of the interior wall portions which constitute the heat absorbing surfaces, substantially as 5 specified.

10. An apparatus of the character described comprising end and intermediate sections enclosing an ash pit, a fire pot, and a combustion chamber; each of said intermediate sections including a continuous, peripheral water compartment comprising vertical side members extending throughout the height of said section and transverse members connecting said vertical members 10 at their upper and lower ends, said vertical members being provided with inwardly projecting portions extending throughout a portion of the height of said combustion chamber and terminating intermediate the 15 upper and lower ends thereof, a hollow water member connecting said inwardly projecting portions adjacent to their upper ends, the projecting portions of the adjacent sections being spaced from one another 20 to form passages communicating with said combustion chamber to conduct the products therefrom, substantially as specified.

11. An apparatus of the character described comprising end and intermediate sections enclosing an ash-pit, a fire pot and a combustion chamber; each of said intermediate sections including a continuous peripheral water compartment comprising vertical side member and transverse members 30 connecting said vertical side members at the upper and lower ends, inwardly projecting water members extending from said side members above the firepot, hollow water members connecting said inwardly project- 35

ing portions and forming intermediate the 40 same and the upper vertical connecting member a series of openings constituting a main flue, the projecting portions being arranged in spaced relation to each other to 45 form passages for the products of combustion, substantially as specified.

12. An apparatus of the character described comprising end and intermediate sections enclosing a fire pot and a combustion chamber; said end and intermediate 50 sections having their entire outer wall portions exposed and constituting heat emitting surfaces whose total area is substantially double that of their interior wall portions which constitute the heat absorbing surfaces, 55 substantially as specified.

13. An apparatus of the character described comprising end and intermediate sections enclosing a fire pot, a combustion chamber and a main flue; each of said intermediate sections including a continuous peripheral water compartment, and said end and said intermediate sections having their entire outer wall portions exposed and constituting the heat emitting surfaces whose total area is substantially double that of the interior wall portions which constitute the heat absorbing surfaces of the apparatus, 60 substantially as specified.

Signed at the city of Buffalo, county of 70 Erie and State of New York, this 29th day of May, one thousand nine hundred and seventeen.

ANDRÉ M. MERTZANOFF.
